UNITED STATES PATENT OFFICE.

WILLIAM A. TRUE, OF NATOMA, KANSAS.

BAND-CUTTER AND FEEDER.

No. 869,113.

Specification of Letters Patent.

Patented Oct. 22, 1907.

Application filed October 3, 1906. Serial No. 337,211.

To all whom it may concern:

Be it known that I, WILLIAM A. TRUE, a citizen of the United States, residing at Natoma, in the county of Osborne and State of Kansas, have invented new 5 and useful Improvements in Band-Cutters and Feeders, of which the following is a specification.

My invention contemplates certain new and useful improvements in band cutters and feeders for threshing machines, and the invention has for its object an 10 improved construction of machine of this character which, by the use of an improved arrangement of rotary band knives and vibratory knives, together with straw forks or picks to force the grain against the cutting knives, will feed the grain properly to the threshing 15 machine without any jerking motion of the feeder or slugging of the cylinder, the invention embodying an automatic governor mechanism which can be readily adjusted so that the machine will feed at any desired speed:

20 For a full understanding of the invention and the merits thereof and also to acquire a knowledge of the details of construction of the means for effecting the result, reference is to be had to the following description and accompanying drawings, in which:

25 Figure 1 is a vertical longitudinal sectional view of my improved band cutter and feeder; Fig. 2 is a top plan view thereof; Fig. 3 is a side elevation, on an enlarged scale; Fig. 4 is also a side elevation, but looking from the opposite side from that shown in Fig. 3; Fig. 5 30 is a detail perspective view of one of the rotary band knives at the receiving end of the casing, the blades and shaft of said knife being shown detached from each other, but in juxtaposition; Fig. 6 is a sectional and assembled view of the parts illustrated in Fig. 5, the section 35 being taken on the line $x-x$ of Fig. 5; Fig. 7 is a detail side elevation of one of the straw hooks; Fig. 8 is a detail view of one of the belt tighteners hereinafter specifically described; and, Fig. 9 is a detail perspective view of the set of straw picking fingers and the bars 40 which carry them.

Corresponding and like parts are referred to in the following description and indicated in all the views of the drawings by the same reference characters.

At the receiving end of the framework or casing 1 a 45 transversely extending shaft 2 is mounted, and upon this shaft is a plurality of rotary band knives 3 spaced from each other in transversely extending series. Each of the knives 3 embodies a plurality of pairs of blades 4, and the complementary members of each pair are provided respectively with end recesses 5 and 6 adapted to embrace the shaft, and with hooks 7 adapted to engage slots 8 in the opposite blade, so as to detachably connect the blades together upon the shaft.

At both sides of the casing 1 at the receiving end 55 thereof, I provide automatic grain hooks 9 adapted to pull the grain in that hangs over the side of the con-

veyor or carrier, and these grain hooks 9 are secured to straps 10 encircling eccentrics 11 on the shaft 2. At one end, each of the hooks 9 is pivotally connected to a link 12 suspended from a bracket 13 on the inside of 60 the casing, as best shown in the longitudinal sectional view. By this means, as the shaft 2 turns, the grain hook 9 will receive an oscillating or vibrating motion, so as to pull the grain in that hangs over the side of the carrier.

65 14 designates the carrier which is in the form of an endless apron, and 15 designates one supporting roller for said apron, said roller being mounted upon a shaft 16 journaled in brackets on posts of the casing 1. A sprocket wheel 17 is secured upon the shaft of the roller 70 15 and receives its motion by means presently herein-after described.

75 As the grain passes the rotary band knives 3, it is caught by the straw picking fingers 18 which are secured to and project downwardly from longitudinally extending bars suspended from and actuated by cranked shafts 19 extending transversely of the casing and mounted in suitable boxings 20, as shown. Underneath the straw picking fingers 18 is the grain pan 21 which is suspended for a vibratory motion by means 80 of hangers 22 secured at their upper ends to the brackets 23 on the outer sides of the casing 1. The grain pan 21 is provided with a series of longitudinally extending and transversely spaced "fish-backs" or toothed bars set on edge, the same being designated 24, and between 85 said bars, the grain pan is provided with a preferably square shaft 25 upon which a series of slanting and vibratory knives 26 are secured, the knives alternating with the "fish-backs." The grain pan 21 receives its motion by means of a pitman 27 which is secured thereto and which is also operatively connected to the eccentric 90 28 of a shaft 29 mounted in the hangers 30 at the lower front end of the framework or casing 1.

95 As the grain passes the rotary band knives 3, it is engaged by the straw picking fingers 18 which force it against the knives 26 and the latter help to tear the straw to pieces so as to distribute the same evenly into the threshing cylinder. The knives 26 not only serve to assist in cutting the bands in the bound grain, while they also cut the matted and tangled headed grain, 100 and also shake the grain up thoroughly from the bottom, so that the "fish-backs" 24 of the grain pan will deliver the grain evenly into the threshing cylinder, thereby preventing any slugging and jerking of the machinery.

105 In order to drive the various parts of the machinery, the following mechanism is utilized. The main drive shaft 2 is provided with the main drive belt wheel 32 over which the main belt 33 travels, said belt receiving its motion from the threshing machine and adapted to run the entire band cutter and feeder. Said belt 110 may be provided with a tension device or roller 34 which works on the small shaft extending outwardly

from the bracket 35 secured to the casing 1. The lug 36 is tightened to the small shaft 37 by means of a set screw 38. 39 designates a spring which starts at the upper left hand corner of the frame of the tension or 5 tightening roller 34 and rests firmly against the corner of the frame 39 and passes downwardly to the shaft 37. It thence goes over the shaft 37 and passes around under it and then back again and finally under the side lug 36 and almost to the top of the frame 39. The spring 10 then crosses over the lug 36 and back to the shaft encircling it several times and finally resting firmly against the underside of the frame 39 so as to complete the tension means for the tightening roller 34. On the drive shaft 2 there is also mounted a band wheel 40 15 over which the belt 41 passes. This band also passes around the pulley 42 on the shaft 29 which drives the vibrating grain pan 21, and thence the belt passes over the pulley 43 which is keyed or otherwise rigidly secured to one of the crank shafts 39 that actuate 20 the vibratory grain picking fingers 18. The belt 41 then passes underneath the tightener 44 and back over the band wheel 40. The tightener 44 is an idler which is journaled within a bracket 45 pivotally mounted on one of the sills of the casing 1 and held at the proper 25 tension by means of a hand rod 46 which is secured to said bracket and provided with a series of notches, any one of which may be caused to receive a locking pin 47 on the casing. At the opposite side of the machine, the main drive shaft 2 carries a spur pinion 48 which 30 meshes with a similar but larger gear wheel 49 mounted on the shaft 50. On the shaft 50 is a sprocket wheel 51 which is connected by a chain 52 to the sprocket wheel 17 on the shaft 16. This latter shaft drives the grain carrier 14. The sprocket 51 is loose on the shaft 35 50 and may be coupled thereto by means of the oppositely disposed clutches 53 adapted for frictional engagement with the rim of the gear wheel 49.

Upon the main drive shaft 2 is keyed or otherwise secured a governor frame embodying a series of radial 40 arms 54 which carry spring retracted rods 55 having friction shoes 56 at their outer ends and which also carry weighted governor arms 57. These arms 57 are adapted to swing outwardly by centrifugal force and press against spring retracted rods 55 so as to force the 45 friction blocks 56 into engagement with rim of the wheel 57. The coil springs of the rods 55 may be adjusted at their inner ends with set nuts 58, thereby making the governor a double adjustable governor.

It is to be understood that the gear wheel or pinion 50 48 is on the rear side of the governor wheel 57 and that it has a square shoulder on one hub adapted to fit in a groove in the hub and the governor wheel 57. The weights of the arms 57 and the jamb nuts or set nuts

58 of the rods 55 may be adjusted according to the speed required, and hence as the speed runs up, the 55 weights will pull the governor arms outwardly and push the spring retracted rods 55 outwardly so as to frictionally engage the blocks 56 with the rim of the wheel 57. On the other hand, when the speed runs down below the normal or regular threshing speed, it 60 is obvious that the friction blocks 56 will be disengaged from the wheel 57, until the speed again reaches the normal point. By this means, the feeding of the grain is automatically controlled as well as the movements of the other parts so that the grain will be properly fed 65 in the threshing cylinder and prevent any jerking motion of the feeder, or slugging of the cylinder.

59 designates a sector which is mounted at one side of the casing. On this works a hand controlled lever 60 which is provided with the usual hand retracted 70 detent and the express purpose of the lever 60 is to provide means so that the clutches 53 may be uncoupled manually to stop the feed at any time. Hence, if a pitch fork or any article should by accident get into the feeder, the feed may be stopped until the 75 fork or article can be removed, before it reaches any portion of the machinery to do any damage.

Having thus described the invention, what is claimed as new is:

1. In a band cutter and feeder, the combination of a 80 casing, means at one end of the casing for carrying grain into the same, means within the casing for feeding the grain through the casing, and agitating the grain, such last named means including grain picking fingers and a grain pan, and means for actuating the same and a series 85 of rotary band knives mounted at the receiving end of the casing, a shaft upon which said knives are mounted, means for rotating said shaft, said knives embodying blades arranged in pairs and the complementary blades of each pair having end recesses by which they are adapted to embrace 90 the shaft and with interengaging hooks and slots, as and for the purpose set forth.

2. In a band cutter and feeder, the combination of a casing, a series of rotary band knives mounted in said casing, a pair of transversely extending crank shafts journaled in the casing in the rear of said knives, longitudinally extending bars secured to the cranks of said shafts and provided with depending grain picking fingers, a grain pan mounted to vibrate underneath said fingers and provided with a series of "fishbacks" and vibratory knives arranged alternately, a carrier adapted to pass the grain into the casing, a drive shaft upon which the rotary band cutters are mounted, an operative driving connection between the said drive shaft, the grain carrier, the grain pan, and one crank shaft, governor mechanism adapted to control 105 the speed of said parts, and manual means for throwing the feeder out of gear at the will of the operator.
